NECK, OF DORCHESTER, MASSACHUSETTS

CALENDER ROLL FILLING

Application filed May 11, 1929. Serial No. 362,435.

This invention relates to calenders and supercalenders and calender rolls, but more specifically to an improved heat-resistant filling for such calender or supercalender 5 rolls.

The usual calender or supercalender roll is made up of a metal core having a filling of paper or cotton cloth mounted thereon, and two end plates serving to compress and align 10 the paper or cotton filling.

Such filled rolls have come to be generally adopted for such purposes as calendering or supercalendering paper or cloth and similar materials, and have proven to be successful 15 save in one particular. It has been observed that after the roll has been run for some time, the filling of paper, cotton, etc., begins to crack or check off in small pieces, especially near the ends of the roll, and this necessitates 20 either regrinding the roll or refilling it. It has long ago been understood that this checking or cracking of the filling is due to the heating up of the roll filling. At first this heating up of the roll filling was attributed to 25 frictional heat generated on the surface of the filling by the passage of the paper under pressure through the nip of the rolls in the calender, supercalender, or press rolls. However, it was later shown and proven that if 30 the filling of the roll be removed carefully, the cracking or checking of the roll filling is more pronounced at or near the center radius than at the surface thereof. This indicated that the cracking or checking of the filling was 35 due to heat passing from the metal or steel core out through the filling of the roll.

To overcome this, the steel core was drilled clear through from end to end, and water-cooled. This resulted in greatly decreasing 40 the cracking or checking of the filling, but did not entirely eliminate it. However, the life of the core was greatly increased, and this water-cooling of filled press, calender, and supercalender rolls has come into general 45 use.

To the end of still further decreasing the checking and cracking of the filling, and to still further increase the life of the filling, I have carried out numerous experiments over 50 a long period of time, and have finally de-

vised a special filling which is less susceptible to cracking and checking than any here-
tofore used.

My invention may best be understood by reference to the accompanying drawings. 55 Figure I is a front view of the usual calender or supercalender roll. In this figure, (a) is the core of metal, (b) is the water-cooled channel, (c) is the two end plates for compressing the filling, (d) is some of the usual 60 filling. Figure II is a side view of this same roll.

The roll may be filled by several methods. The usual method is to cut out round sections from paper or cotton, such as shown in 65 Figure III, mount them on the metal or steel core, and compress them between the end plates. This is known as a lamination-filled roll. Another method is to wind paper or cotton cloth, etc., onto and around the core. 70 This method, however, has the disadvantage of leaving an unsealed or lapped end or seam. Still another method is to shrink onto the core a wool or woolen jacket, thus eliminating the seam or end flap. Finally rolls 75 have been filled by using more or less plastic materials, like rubber, etc., to fill in the space between the end plates.

However all of these filled rolls, regardless 80 of the filling used or of the method of filling, and even when water-cooled through the core, are not entirely satisfactory in that they still crack or check especially at or near the ends of the roll, and thus after a time render the filling defective and incapable of further use 85 until reground or refilled. It is to overcome this defect that I have devised my present invention.

According to it, I take a heat-resistant material, such as asbestos, either in the form of asbestos paper, asbestos cloth, pressed asbestos, or asbestos and a binder, or any asbestos-containing material, or rubber, in the form of sheets, rubber impregnated materials, or plasticized rubber, or heat-resistant synthetic resins either as such or comminuted with fillers or materials impregnated with such resins as bakelite for example, or any heat-resistant material, and assemble it as part of the filling. 100

One form of practicing the invention is to take some asbestos paper or asbestos cloth and cut it into sections of the same size as the regular paper or cloth filling, and insert several of these laminations at or near the end of the paper or cloth filling, thus giving us a section of heat-resistant material at or near the ends of the regular filling. Such a heat-resistant section is shown at (e) of Fig. I. 10 The laminations used may be of any suitable thickness, and it has been found that asbestos paper of ten mils (0.010 inches) thickness is suitable. The width of the assembled laminations may vary, and be as little as $\frac{1}{2}$ an 15 inch or as great as 6 or 8 inches depending on the heat characteristics of the press rolls, calender stack or supercalender stack, with which it is used.

As to the exact location of the heat-resistant sections, I have found that the best results are obtained by having them located at the very end of the roll-filling, and a width of one inch gives very good results. However, I have found that good results may also 25 be obtained by locating the heat-resistant sections a little nearer the center of the roll and somewhat in from the ends of the roll.

The effect of this heat-resistant section such as one made from asbestos, or asbestos-containing material, bakelite or bakelite-containing material, or rubber or rubberized material, or any other heat-resistant material, is to prevent the heat from passing from the metal end pieces to the regular filling of paper 30 or cotton, thus preventing the cracking or checking of the filling. This heat may come from either the high pressure steam used to heat the steel rolls usually found in supercalenders, or it may come from steam sprays 35 or also from frictional heat. And the heat-resistant material itself, being heat-resistant does not check or crack, so that the life of the roll-filling is prolonged. In point of fact, 40 after many trials with this heat-insulated section, I have found that the life of a roll-filling may be increased by fifty percent by its use.

It will be apparent, of course, that the heat-resistant filling or section may be affixed 50 to the roll either as laminated sheets, or as material wound around the core until the desired thickness is obtained, or as a built-in section of plasticized material, or by other well-known means. And likewise, the invention is applicable to rolls having fillings 55 made from laminated sections, wound rolls, or shrunken fillings, or plasticized fillings, or fillings made in situ, or any type of filling, however prepared or assembled. The invention 60 may thus be practiced on any filled roll of any type, irrespective of the nature of the filling.

The filling proper is usually made up of 65 paper or cotton laminations, and is herein-after referred to as the "mid-section" in

order to distinguish it from the "heat-resistant section", which is usually located at or near ends of the filling.

By the term "calender roll" I mean any 70 roll used for pressing or calendering or supercalendering fibrous or other materials, the roll having a filling of fibrous or other material. These rolls are quite generally used in supercalenders for finishing paper, and are most generally run in contact with a metal or steel roll. However, some calender or supercalender stacks have two filled rolls 75 running in contact with each other in order to make possible a finishing of both sides of the paper or fibrous sheet.

This invention is thus adapted to be used 80 with any press, calender, or supercalender roll or stack, irrespective of the nature, kind, or type of filling proper used, and irrespective of the nature, kind, or type of heat-resistant material or substance employed, or of the exact location or width of the heat-resistant material, or of the width of the filling proper.

By the term "asbestos" as used in the claims 90 appended hereto, I mean any material composed of or containing asbestos in reasonably prepondering amount, such as asbestos paper, pressed asbestos, asbestos mixed with a fibrous or other binder, etc.

There are various heat-resistant materials 95 that may be used in practicing my invention, and these heat resistant materials may be used in sections having varying widths, and located in various places along the core of 100 the roll, or in the filling thereof; and there are various other modifications in materials, proportions, locations, widths, and so forth, which may be used in practicing my invention, but all such variants are to be considered 105 as within the spirit, scope, and purview of my invention, as defined in the appended claims.

What I therefore claim and desire to secure 110 by Letters Patent is:

1. A calender roll filling composed of a wide, fibrous, substantially cellulosic mid-section, and comparatively narrow sections 115 of heat-resistant material located at or near the ends thereof.

2. A calender roll filling composed of a wide, fibrous, substantially cellulosic mid-section, and comparatively narrow sections of asbestos material located at or near the ends thereof.

In testimony whereof I affix my signature.

JAMES FISH.
